UNITED STATES PATENT OFFICE.

JOHN F. WHITE, OF CHICAGO, ILLINOIS, ASSIGNOR TO WHITE PRODUCTS CO., OF CHICAGO, ILLINOIS, A CORPORATION OF ILLINOIS.

HOOD LATCH.

Application filed April 27, 1921. Serial No. 464,882.

To all whom it may concern:

Be it known that I, JOHN F. WHITE, a citizen of the United States, residing at Chicago, in the county of Cook and State of Illinois, have invented certain new and useful Improvements in Hood Latches, of which the following is a specification.

The present invention pertains in general to latches, and contemplates specifically the provision of a novel hood latch for motor vehicles.

The principal purposes of the invention, broadly stated, are the provision of a latch of this nature which is of a simple durable construction, which is easily manipulated, and which is characterized by an extremely pleasing inconspicuous appearance.

One of the most salient features of the latch lies in its efficient manner of operation, wherein the strong spring tension provided for maintaining the hood in its fastened position is applied thereto without effort by a progressively increasing leverage through the fulcrumed movement of the latch handle.

Another important feature resides in the automatic interlocking of the latch under the previously mentioned spring tension, whereby forces tending to raise the hood when the same is fastened merely result in a more secure locking of the latching means.

Other advantages present in this invention will be appreciated as the nature of the same is better understood from the following description and accompanying drawings wherein is set forth what is now considered to be two preferred embodiments of the invention. The particular embodiments disclosed are merely illustrative however and are not intended to be construed as a restriction on the spirit of the invention or as an unnecessary limitation of the scope of the claims.

In the drawings—

Fig. 1 is a side elevation of the latch in its fastened position, showing in section the hood, keeper and latch pivot;

Fig. 2 is a rear elevation of the latch and keeper as viewed from within the hood;

Fig. 3 is a view, corresponding to Fig. 1, of a modified form of the latch; and

Fig. 4 is another view, corresponding to Fig. 2, of the modified form.

Referring in detail to the drawings, and particularly to Figs. 1 and 2 thereof, it will be observed that the side of the hood 10

which is hinged to the upper portion of the same at 11 contacts, when lowered into the closed position here illustrated, against an upwardly bent flange 12 of a positioning strip carried on the chassis 13 of the vehicle. 60

An escutcheon plate 14 is secured to the outer side of the hood by bolts 15, and, while adding distinctly to the appearance of the latch, serves as a reinforcement for the hood at that point. A narrow vertical rectangular slot 16 is cut in the plate and hood, and receives the hook member 17 of the latch. This member comprises a stem 18 which is provided at its outer end with a transverse handle 19, and, at its inner end, with a flat 70 head 20 of substantially semi-circular shape. The straight edge 21 of this semi-circular head lies at an obtuse angle to the axis of stem 18 and, when the hood is closed and the latch fastened, substantially fills the slot 75 16 flush with the escutcheon plate 14.

A deep angular notch 22 is cut in the curved edge 23 of the head 20 adjacent the top of the straight edge 21, and constitutes a keeper-engaging hook. A portion of the 80 curved edge 23 adjacent the stem 18 and diametrically opposite the notch 22 is also cut away whereby to form a shoulder 24 adapted to interlock, as shown in Fig. 1, with the inner bottom edge 25 of the slot 16 85 when the latch is in its fastened position.

An elongated slot 26 is formed in the head 20 with its axis approximately bisecting the angle presented by the intersection of the extension of the stem axis and the head 90 diameter on which the shoulder 24 and notch 22 are disposed. This slot is rounded at both ends and provides a pivotal fulcruming bearing for the hook member 17 on a transverse pin 27 which is journalled at either 95 end in small brackets 28 fixedly positioned on the inner side of the hood at both sides of the slot 16. The center of the rounded end of the slot adjacent the stem 18 is the center of the semi-circular curved edge 23 100 of the head, and also the axis on which the pin 27 normally journals the hook member when the latter is being turned into its fastened position.

The keeper of this latching device comprises a plate 29 which is bolted at one end to the chassis, and is bent slightly upward at its other end and there provided with two spaced threaded cylindrical lugs 30. Spiral springs 31, the coils of which 110

when unstressed are substantially closed, telescope over these lugs and are secured thereto in threaded engagement with the same. These springs extend upwardly at 5 the same slightly oblique angle as the lugs and are secured in a similar manner about the downwardly depending ends of an inverted U-shaped yoke 32. This yoke of the keeper, when not pulled upwardly by 10 the co-acting hooking member 17 against the resistance of the coil springs 31, is normally supported by the springs at approximately the height of the pin 27, being deflected and pressed laterally inward by the 15 head 20 as shown in dotted lines in Fig. 1. When the hood is not in this closed position however the resilient construction of the keeper causes the spring sides thereof to assume a position co-axial with that 20 occupied when in the fastened and consequently stressed position.

It should of course be understood that, while this particular type of keeper is disclosed, any keeper having similar flexible 25 and yielding properties may be employed with equal success.

The operation of the latch will now be described. Assuming that the hooking member is in the position shown in dotted 30 lines in Fig. 1 with its handle raised and its notch 22 engaging the keeper, it is merely necessary to push downwardly the handle in order to fasten the device. As the distance from the pin 27 to the bottom of 35 the slot 16 is approximately equal to the radius of the curved edge of the head 20 the exposed portion of the curved edge 23 of the head will pivot about the pin 27 into the slot 16 as the springs 31 become 40 elongated and tensioned upon being raised by the leverage applied thereto through the handle on its fulcruming pin 27. As the handle is pushed into a lower position and the slot 26 consequently becomes more 45 nearly vertical the resistance offered by the keeper in being raised is gradually shifted from the pivotal fulcruming pin 27 to the bottom of the slot 16 upon which the curved edge 23 rides. As the shoulder 24 of the 50 curved edge reaches the edge 25 of the bottom of the slot, the pin 27 becomes relieved of practically all of its load, and the bottom of the slot 16 receives through the head 20 the force of the stressed springs of the 55 keeper. When the handle is pushed to its lowest position the curved edge 23 of the head rides off the bottom of the slot 16 and permits the hooking member 17 to move bodily downward under the action of the 60 keeper, whereby the shoulder 24 of the head interlocks with the edge 25 of the slot 16. This downward movement of the hooking member changes of course the relative position of the pin 27 in the pivoting slot 26, 65 and in so doing cams the upper hook end

of the head outwardly whereby the point of application of the tension of the keeper is shifted more nearly over the pin 27 and the straight edge 21 of the head is moved outwardly into a position flush with 70 the escutcheon plate 14.

The latch is now securely fastened, and any forces tending to raise the hood will obviously result in a more secure interlocking of the latch head and the slot 16. 75

To unfasten the latch it is only necessary to pull upwardly on the handle until the shoulder 25 of the head cams over the bottom of the slot 16, whereupon the tension of the keeper will assist to further turn the 80 hooking member until it assumes the unlocked position.

The slot 26 in the latch head may be continued in the direction of the hooking notch 22 a short distance further than is 85 necessary to accommodate the pin 27 during the fastening operation of the latch. This extension of the slot permits the hooking member to be drawn further away from the keeper when said member is pulled upwardly 90 in the act of raising the hood. Although the construction as hereinbefore set forth of the slot 26 in the head of the hooking member is considered preferable, measurably good results may also be obtained by 95 the employment of other shaped apertures in lieu thereof, such for instance as a circular one which would include within its area the two relative positions assumed by the pin 27 and shown in Fig. 1. 100

The other embodiment of the invention, which is illustrated in Figs. 3 and 4, will now be described. Inasmuch as the two forms of the invention are in many respects substantially identical, the following description will be confined for the most part to the points wherein this second form of the invention differs in construction from the first. 105

The head 20 of the hooking member 17 110 is provided in this second embodiment with a circular aperture 33 which snugly fits about a journaling pin 34 corresponding to the pin 27 of Fig. 1. This pin is in turn supported at both its ends in ears 35 which 115 are preferably formed as integral inward projections from the plate 14 which borders the slot 16 on the outer face of the side of the hood 10. The upper surfaces of the ears 35 are provided with laterally aligned 120 notches 36 which are adapted to receive the yoke 32 of the then stressed keeper when the latch is in its fastened position, as shown in full lines in Fig. 3. 125

A deep angular notch 37, substantially similar in shape and position to the notch 22 of the first described embodiment, is cut in the head 20 of the hooking member, and is adapted to engage the yoke 32 of the keeper and raise it into a position against 130

the shoulders 38 which constitute the outer sides of the notches 36, whereupon a slight further movement of the notch 37 and contained yoke 32 toward the ears 35 by the 5 continued downward movement of the latch handle 17 causes the yoke to cam over said shoulders 38 and become firmly seated in the notches 36 on the far side thereof.

The bottoms of the notches 36 and 37 10 are disposed at substantially the same distances above the pivoting pin 34 whereby to eliminate any play of the hooking member 17 when the latch is in its fastened position. Both sides 39 and 40 of the notch 37 15 are of course a greater distance above the pin 34 than the shoulders 38 of the ears 35 in order that upon pivotal movement of the head 20 in either direction one of the sides 39 or 40 of the notch will engage the keeper 20 and cause the same to cam into or out of the notches 36 over the shoulders 38.

Inasmuch as the head 20 in this second form of the invention does not ride, through a portion of its movement, on the bottom of 25 the slot 16, the contour of this portion of the head need not be arcuately formed with its center at the pivoting point, but may, on the other hand, be of any shape which will in its downward movement serve to 30 cam the yoke 32 outwardly whereby to subsequently snap inwardly into the notch 37.

In both embodiments of the invention it 35 will be noted that the angle formed by the yoke-engaging notch in the head 20, the fulcrum point at the pivot pin and the handle is obtuse. This construction results in an increased leverage applied in latching the device commensurate with the increasing resistance of the keeper as the latter is 40 stressed into the fastened position.

I claim:

1. In a hood latch, a hooking member 45 projecting exteriorly of the hood, a fulcrum adapted to cooperate with said member, a keeper carried by the stationary structure 50 interiorly of the hood, and means functioning when the hooking member in engagement with the keeper has reached the fastened position of the latch for securing the member in said position.

2. In a hood latch, a hooking member 55 projecting exteriorly of the hood, a fulcrum adapted to cooperate with said member, a resilient keeper carried by the stationary 60 structure interiorly of the hood, and means functioning when the hooking member in engagement with the keeper has reached the fastened position of the latch for securing the member in said position.

3. In a hood latch, a hooking member 65 projecting exteriorly of the hood, a fulcrum adapted to cooperate with said member, a keeper carried by the stationary structure 70 interiorly of the hood and having a spring-supported yoke, and means functioning

when the hooking member in engagement with the keeper has reached the fastened position of the latch for securing the member in said position.

4. In a hood latch, a hooking member 75 projecting exteriorly of the hood through an aperture therein, a fulcrum adapted to cooperate with said member, a keeper carrier by the stationary structure interiorly of the hood, and means functioning when the 80 hooking member in engagement with the keeper has reached the fastened position of the latch for securing the member in said position, said member when in its fastened position serving to substantially close the aperture in the hood.

5. In a hood latch, a hooking member 85 projecting exteriorly of the hood, a fulcrum adapted to cooperate with said member, a keeper carried by the stationary structure 90 interiorly of the hood, and means functioning automatically when the hooking member in engagement with the keeper has reached the fastened position of the latch for securing the member in said position. 95

6. In a hood latch, a hooking member 100 projecting exteriorly of the hood and provided adjacent one end with a hooking portion, a fulcrum adapted to cooperate with said member intermediate the length thereof, a keeper carried by the stationary structure 105 interiorly of the hood, and means functioning when the hooking member in engagement with the keeper has reached the fastened position of the latch for securing the member in said position. 110

7. In a hood latch, a hooking member 115 projecting exteriorly of the hood and provided adjacent one end with a hooking portion and adjacent the other end with a handle portion, a fulcrum adapted to cooperate with said member intermediate the hooking and handle portions thereof, a keeper carried by the stationary structure 120 interiorly of the hood, and means functioning when the hooking member in engagement with the keeper has reached the fastened position of the latch for securing the member in said position. 125

8. In a hood latch, a hooking member 130 projecting exteriorly of the hood and provided adjacent one end with a hooking portion and adjacent the other end with a handle portion, a fulcrum adapted to cooperate with said member intermediate the hooking and handle portions thereof, a keeper carried by the stationary structure interiorly of the hood, and means functioning when the hooking member in engagement with the keeper has reached the fastened position of the latch for securing the member in said position, said hooking portion, fulcrum and handle being disposed to form therebetween an upwardly obtuse angle.

9. In a hood latch, a hooking member 135

- provided with a hook a shoulder and an aperture, a keeper adapted to engage with said hook, a pin passing through said aperture and occupying only a portion thereof 5 at one time, and means for engaging said shoulder upon the bodily downward movement of the hooking member when assuming its fastened position, whereby said position of the member is maintained.
- 10 10. In a hood latch, a hooking member provided with a hook, a shoulder and an elongated aperture, a keeper adapted to engage with said hook, a pin passing through said aperture and occupying only a portion thereof 15 at one time, and means for engaging said shoulder upon the bodily downward movement of the hooking member when assuming its fastened position, whereby said position of the member is maintained.
- 20 11. In a hood latch, the combination with a hood having a slot in the side thereof, of a hooking member composed of a handle and a head portion provided with a hook and a shoulder, a keeper adapted to engage with 25 said hook, and means for mounting said member in said slot whereby upon reaching its fully fastened position the hooking member will shift bodily and the shoulder thereof will interlock with the bottom of the slot 30 in the hood to maintain the latch fastened.
12. In a hood latch, the combination with a hood having a slot in the side thereof, of a hooking member composed of a handle and a head portion provided with a hook and a shoulder, a keeper adapted to engage with 35 said hook, and means for mounting said member in said slot whereby upon reaching its fully fastened position the hooking member will shift bodily toward the keeper and the shoulder thereof will interlock with the 40 bottom of the slot in the hood to maintain the latch fastened.
13. In a hood latch, the combination with a hood having a slot in the side thereof, of a hooking member composed of a handle and a head portion provided with a hook and a shoulder, a keeper adapted to engage with 45 said hook, and means for mounting said member in said slot whereby upon reaching its fully fastened position the hooking member will automatically shift bodily downward and the shoulder thereof will interlock with the bottom of the slot in the hood to 50 maintain the latch fastened.
- 55 14. In a hood latch, the combination with a hood having a slot in the side thereof, of a hooking member composed of a handle and a head portion provided with a hook and a shoulder, a resilient keeper adapted to engage with 55 said hook, and means for mount-
- ing said member in said slot whereby upon reaching its fully fastened position the hooking member will shift bodily and the shoulder thereof will interlock with the bottom of the slot in the hood to maintain the 65 latch fastened.
15. In a hood latch, the combination with a hood having a slot in the side thereof, of a hooking member composed of a handle and a substantially semi-circular head portion provided adjacent one end of its arcuate edge with a hook and adjacent the other end of said edge with a depression whereby to constitute a shoulder of said last mentioned end, a bearing slot in said head portion having its end which is nearer said shoulder substantially in the center of the arcuate edge of the head portion, a pin mounted on the hood across the slot therein and passing through the bearing slot of the 70 head portion, and a keeper adapted to engage with said hook.
16. In a hood latch, the combination with a hood having a slot in the side thereof, of a hooking member composed of a handle and a substantially semi-circular head portion provided adjacent one end of its arcuate edge with a hook and adjacent the other end of said edge with a depression whereby to constitute a shoulder of said last 75 mentioned end, a bearing slot in said head portion having its end which is nearer said shoulder substantially in the center of the arcuate edge of the head portion, a small cylindrical pin mounted on the hood across the 80 slot therein and passing through the bearing slot of the head portion, and a resilient keeper adapted to engage with said hook.
17. In a hood latch, a hooking member provided adjacent one end with a hooking 85 portion and adjacent the other end with a handle portion, a fulcrum adapted to cooperate with said member intermediate the hooking and handle portions thereof, and a keeper adapted to engage with said hooking portion, the angle formed between the hooking portion and fulcrum and the handle portion and the fulcrum being upwardly obtuse whereby a downward pressure on the handle portion results in a progressively increasing leverage against resistance to upward movement of the hooking portion.
